UNITED STATES PATENT OFFICE.

LEE LIVINGSTON ABBOT AND WILLARD N. MUNROE, JR., OF AUBURN, MAINE, ASSIGNEES TO THE MUNROE SHOE COMPANY, OF AUBURN, MAINE, A CORPORATION OF MAINE.

SHOE-COUNTER PRESSER.

Application filed December 27, 1924. Serial No. 758,471.

Our present invention relates to shoe presses, and more particularly to an improved press for forming and shaping the heel part of a shoe after the shoe is otherwise complete.

It is admittedly old to press or compress a heel, and also admittedly old to compress and shape a counter before said counter is placed in a shoe structure. Such heel pressing or counter pressing and forming do not affect, materially, the shape of the shoe, and particularly the shape of the completed shoe. The finished shape of a shoe, therefore, has been dependent on the degree of skill exercised in the manufacturing process and, admittedly, shoes vary in shape.

With a view to securing uniformity in the shape of the finished shoe, and also for the purpose of giving such shoe a trim appearance and a form that will fit snugly to the foot of the wearer, we have devised the subject matter of the present invention. Our invention consists primarily in taking a completed shoe and compressing the heel portion thereof to give a final set or shape to the shoe, and consists particularly in the means for applying a gradual pressure to the heel portion of a shoe, such pressure beginning at the junction point of the heel of the shoe and the heel proper and extending progressively upward beyond the counter. This progressive pressure is an important element in our invention as, where it is attempted to compress the heel portion of a shoe by applying an equal pressure simultaneously over the desired surface to be compressed, there is danger of the upper leather wrinkling at the junction of the heel with the heel portion of the shoe.

The principal object of our invention, therefore, is an improved compressing and forming device for the heel portion of boots and shoes.

Another object of our invention is an improved means for applying progressive pressure to the heel portion of a shoe.

Other objects and novel features of the construction and arrangement of parts comprising our invention will appear as the description of the invention progresses.

In the accompanying drawings illustrating a preferred embodiment of our invention,

Fig. 1 is a plan view;

Fig. 2 is a side elevation;

Fig. 3 is an end elevation looking from right to left in either Figs. 1 or 2, and

Fig. 4 is a view similar to a portion of Fig. 3 and showing the manner in which the progressive pressure is applied to the heel portion of a shoe.

Referring to the drawings, 10 designates a bed plate adapted to be placed on a bench or table, and secured to the base 10 by bolts 11 is a side plate 12. Spaced apart from the side plate 12, lying parallel thereto, and pivotally attached to the base 10 by bolt 13, is a second side plate 14 substantially equal in dimensions to the side plate 12. In order to insure stability of the side plates 12 and 14 on the base 10, we have provided a rectangular strap 15 of metal or other suitable material secured in place by the bolts 11 and 13, and to further strengthen the structure, there is secured near the forward end of the frame member 12 by bolt 11 the forward end of an angle iron 16, the rear end of this angle iron being secured to the strap 15 and to the side plate 14 by bolt 13. Secured to each of the frame members 12 and 14 by screws 17 and extending rearwardly therefrom are members 18, each provided with a perforation at its rear end. Fitting into the perforations and joining the rear ends of the members 18 is a coil spring 19 which tends to swing the forward end of the frame member 14 away from the forward end of the frame member 12. Secured to the inner front faces of the frame members 12 and 14 are cooperating die members 20 and 21 respectively, the form of such die members being such as to conform to the desired shape of the heel portion of a shoe 22 to be compressed.

The frame member 14 adjacent to the die member 21 is perforated and through this perforation passes a cord or belt 23, the end of which is knotted, as indicated at 24, to prevent the member 23 from being drawn through the perforation. The member 12 is perforated in alignment with the perforation in the member 14 and the rope or belt 23 passes through such perforation and over a grooved pulley 25 rotatably mounted on a shaft 26. This shaft 26 is secured to a bracket 27 secured to the outer face of the frame member 12 by screws 28. The rope or belt 23 extends downwardly toward the floor 29 and its lower end is knotted in a perforation 30 formed in a foot treadle 31.

that is pivotally mounted at 32 in a bearing lug 33 which is, in turn, secured to the floor or platform 29.

Referring to Fig. 4 wherein is illustrated 5 the die members 20 and 21 and the relation such die members occupy to the heel portion of a shoe 22 to be operated on, it will be noted that the lower end of the die members 20 and 21 are about to engage the heel 10 portion of the shoe 22 substantially at the junction of the heel 34 with the heel portion of the shoe 22; and it will be obvious that, as the die members 20 and 21 are moved toward each other, the die members 15 20 and 21 will be gradually brought into engagement with the heel portion of the shoe. This action on the part of the die members 20 and 21 prevents wrinkling of the upper leather on the heel part of the 20 shoe and imparts to the finished shoe a trim, neat and uniform appearance.

The operation of our improved device is as follows: No pressure being applied to the treadle 31, the spring 19 will swing the 25 frame member 14 about its pivot bolt 13 so as to move the die member 21 away from the die member 20. The operator, taking a shoe, as 22, places the same between the die members 20 and 21 and gradually applies 30 pressure to the treadle 31. Pressure on the treadle 31 will cause a downward pull on the rope of belt 23; whereupon the frame member 14 with its attached die member 21 will be drawn toward the die member 20 and, referring to Fig. 4 particularly, it will be seen that the die members 20 and 21 will 35 first engage with the shoe structure 22 at the junction point of the heel portion thereof with the heel 34. Pressure being gradually applied, there is a gradual folding or compressing action on the part of the die members 20 and 21 to the heel portion of the shoe, this gradual progressive compressing 40 action resulting in really an ironing out of any wrinkles that there may happen to be in 45

the upper leather. Preferably the shoe 22 is placed in the press right side up, as shown in Figs. 3 and 4 in end elevation, or may be placed in the press with the heel uppermost, as desired. 50

Having thus described our invention, what we claim as new is:

1. In a shoe compressing device, the combination of a pair of cooperating dies adapted to shape and form the heel portion 55 of a completed shoe, and means for moving said associated die members toward each other to apply a progressive compressing action to the heel portion of the shoe:

2. In a shoe compressing device, the combination of a pair of compressing die members, means for moving said die members toward each other, and means for automatically moving said die members away from each other, said die members being formed 60 to apply a progressive compressing action on the heel portion of a completed shoe as the same approach each other:

3. An improved shoe compressing device comprising a platform, a frame member secured thereto, a die structure secured to said frame member, a second frame member arranged parallel to, and pivotally mounted with respect to, the first frame member, a die structure secured to one end 70 of said second frame member and operatively associated with the first said die structure; means normally tending to move said second frame member about its pivot point whereby the die member associated therewith is moved away from the first said die member, and means for moving said second frame member toward the first said frame member to bring the die structures into 75 close association with each other. 80

In testimony whereof, we have signed our names to this specification.

LEE L. ABBOT:
WILLARD N. MUNROE, Jr.
